UNITED STATES PATENT OFFICE.

GEORGE H. GILMAN, OF ST. PAUL, MINNESOTA.

RAILWAY-CAR TRUCK

1,128,771.

Specification of Letters Patent. Patented Feb. 16, 1915.

Application filed May 11, 1914. Serial No. 827,740.

To all whom it may concern:

Be it known that I, GEORGE H. GILMAN, a citizen of the United States, residing at St. Paul, in the county of Ramsey and State of Minnesota, have invented certain new and useful Improvements in Railway-Car Trucks, of which the following is a specification.

My invention relates to trucks for railway cars, particularly trucks of the six wheel type used on passenger cars.

The principal objects of the invention are to do away with the use of elliptical springs, ordinarily employed in car trucks and with them the side bearing arches, truck bolsters and spring planks, thereby providing a less obstructed space under the truck frame for the brake rigging which may, in consequence, be simplified in its construction and more easily repaired when necessary; to provide certain arrangements of the springs whereby the car body will be more efficiently cushioned on its running gear; to provide a truck which will be simpler in its construction, stronger and more durable than the trucks now in use; and furthermore, to provide a construction for a railway car truck which, while quite different in its general organization from the trucks of standard type and an improvement thereon in the several respects above noted, accomplishes said improvements by means of certain parts and devices which can be readily substituted for corresponding parts and devices in trucks of standard makes so that old equipment may be reconstructed to obtain the benefits of the invention with a minimum expenditure for labor and material.

Regarded more specifically, the invention provides in a railway car truck a cushioned or elastic center bearing arranged preferably above the truck frame on which the bolster is sustained and which takes the place of the usual structure made up of the side bearing arches, truck bolsters, spring planks and elliptical springs, these being entirely done away with in the truck of my invention.

The invention further provides a supporting member of new and improved form and construction for sustaining the center

bearing on the truck frame which serves to brace and reinforce the truck frame so as to keep the same from getting out of square. In addition to these features the invention provides a novel arrangement of springs between the equalizer bars and the truck frame which operate, particularly in connection with the elastic center bearing of the truck, to more efficiently absorb shocks and cushion the car body under varying loads than the spring arrangements of the trucks heretofore in use. The invention also provides a telescoping elastic side bearing between the body bolster and the truck frame which is calculated to further carry out one of the general purposes of the invention, namely, to provide efficient means for elastically supporting the car body on the running gear so that the car will run smoothly and evenly. The gradual increase in weight of passenger cars which has been going on for some time, has reached such a point that the spring arrangements in the trucks of standard type are not capable of absorbing the shocks to which they are subjected, particularly when the cars carry a heavy load. The remedy which has been tried is to increase and stiffen the springs but with the result that the springs are altogether too stiff when the cars carry light loads.

My invention provides a radically different arrangement of springs involving a different organization of the other elements of the truck and by these novel arrangements and constructions, accomplishes an elastic or cushioning support for the car body which operates to effectively absorb shocks and vibration with the car either lightly or heavily loaded.

While all of the improvements to be hereinafter described and claimed coöperate one with another and are preferably used in combination substantially as shown, certain advantages might be obtained by the separate use of some of these improvements in trucks of different type and general organization.

The preferred embodiment of the invention combining all of its features of improvements is shown in the accompanying drawings wherein—

Figure 1 is a plan view of the truck; Fig. 2, a side elevation; Fig. 2a a detail view showing the comparative length of the equalizer springs before compression; Fig. 3, a detail plan view of one of the side bearings; Fig. 4, a sectional view on line 4-4 of Fig. 3; Fig. 5, a view, in perspective, of the bearing member on the truck bolster which cooperates with the yieldable bearing shown in the preceding two figures; Fig. 6, a view, in perspective, of a truck frame of ordinary form which may be employed in the construction of the truck of my invention; Fig. 7, a plan view, of the center bearing supporting member which serves also as a reinforcement and brace for the truck frame; Figs. 8 and 9, side views of said supporting member; Fig. 10, a cross sectional view taken on line 10-10 of Fig. 1, and Fig. 11, a plan view of a portion of the supporting member shown in detail in Figs. 7 to 9 inclusive and of the center bearing supported thereon.

Like characters of reference designate like parts in the several figures of the drawings.

Referring to the drawings, 25 designates the body bolster of the car, 26 the body center plate, 27 the truck center plate, 28 the wheels, 29 the axles, 30 the axle boxes, 31 the equalizer bars which are secured to the axle boxes in the familiar manner, 32 the pedestals and 33 the pedestal tie bars, these parts all being, if desired, of familiar construction. A truck frame of common construction may also be employed, a frame of this type being shown in detail in Fig. 6 and consisting of side members or outer wheel pieces 34, end pieces 35, transoms 36 and inside wheel pieces 37 all suitably joined together to form a rigid structure. Supported upon and rigidly connected with the truck frame is a center bearing support 38 (which may be cast integral with the truck frame if a cast steel frame be employed) formed with a central opening 39 and diagonal legs 40 extending preferably to the side members 34 and transoms 36. If the supporting member be made separate from the truck frame, the legs 40 are bolted to the side members 34 and transoms 36, so as to reinforce said truck frame and keep the same from getting out of square.

The center bearing, which carries the entire load of the car and in my truck takes the place of the side bearing arches, truck bolsters, spring planks and elliptical springs of the standard types of six wheel trucks, consists of an upper telescoping member 41 to which the truck center plate 27 is secured (obviously these parts might be made integral), a lower telescoping member 42 and a plurality of coiled springs 43 interposed between the upper and lower tele-

scoping members, the lower member being 65 sustained from the supporting member 40 by means of hangers 44 connected to the supporting member 40 by pivot pins 45 carried in bearings 46 on the supporting member 40 and similar pivot pins 46 which 70 extend through bearings 47 on the lower telescoping member 42. The king pin 48 extends through the bearing plates 26, 27, and preferably also through the telescoping members 41, 42, as shown in Fig. 10. 75 The load on the center bearing is transmitted through springs 43 and the supporting member 40 directly to the truck frame. It is transmitted from the truck frame to the axles of the truck by means of the equalizer bars 31 through springs interposed between the equalizer bars and the side members 34 of the frame. Instead of having one spring between each equalizer bar and the truck frame I preferably employ three 80 springs. The central or master spring 49 is stiffer and heavier than the springs 50, 51 on either side of it, and comes into play only with a heavy load or when a considerable shock has to be resisted. The springs 90 49 and 50 are preferably the same length, the spring 51 being somewhat longer so that it is put under compression before the others. The springs bear at one end on a seating block 52 carried by the equalizer 95 bar and on the other end against a seating block 53 secured to the under side of the corresponding side frame member 34. With a medium load any normal shock is absorbed by the springs 43 of the center bearing and by spring 51 between the frame and the equalizer. With an overload or an abnormal shock springs 49 are compressed.

The truck is preferably provided with elastic side bearings interposed between the 105 ends of the body bolster and the side members of the truck frame, one of these bearings being shown in detail in Figs. 3, 4 and 5. 54 designates a bearing member bolted to the end of the body bolster, 55 an upper 110 telescoping member on which the bearing member 54 rests, 56 a lower telescoping member secured to the side member 34 of the truck frame and 57 springs interposed between the telescoping members 55, 56. 115

It will be seen that in the truck as above described the spaces below the truck frame and between the wheels are practically free of obstructions, whereas in the standard types of six wheel car trucks these spaces 120 are largely filled by the truck bolsters, spring planks and elliptical springs, all of which parts are eliminated in my truck. As a result the brake rigging may be materially simplified and, moreover, a workman 125 making repairs underneath the car has a great deal more room to work in. Furthermore, by providing a center bearing having

a plurality of springs, and by employing a plurality of springs between each equalizer bar and the truck frame, the breaking of a single spring does not disable the car. 5 Furthermore, these arrangements permit, in effect, two spring systems, one which operates when the car is carrying a light or medium load and when the shocks to be absorbed are not violent, and another which 10 comes into play with an overload or with an abnormal shock.

While I have described my invention in certain preferred embodiments, modifications might be devised without departing 15 from the principles of the invention. Therefore I do not wish to be understood as limiting the invention to the precise constructions, arrangements and devices shown and described except so far as it is so limited 20 by the express language of certain of the claims.

I claim:

1. In a railway car truck, the combination with a truck frame and a center bearing 25 plate, of a supporting structure having diagonal legs sustained by said truck frame and means carried thereon providing an elastic support for said center bearing plate.

2. In a railway car truck, the combination 30 with a truck frame and a center bearing plate, of a supporting structure having diagonal legs sustained by said truck frame and means carried thereon providing an elastic swinging support for said center bearing plate.

3. In a railway car truck, the combination with a truck frame and a center bearing 35 plate, of a supporting structure sustained on said truck frame and having a central opening telescoping members in said opening, one of which carries the center bearing plate and the other of which is hung from said supporting structure, and springs interposed between said telescoping members.

4. In a railway car truck, the combination 40 with a truck frame and a center bearing plate, of telescoping members, one of which carries the center bearing plate, hangers providing a sweeping support for the other telescoping member, and springs interposed between said telescoping members.

5. In a railway car truck, the combination 45 with a truck frame, of a center bearing support having diagonal legs with the truck frame, and an elastic center bearing sustained on said support.

6. In a railway car truck, the combination 50 with a truck frame, of a center bearing support having diagonal legs with the truck frame, an elastic center bearing, and hangers for sustaining the same on said support.

7. In a railway car truck, the combination 55 with a truck frame, of a center bearing support having diagonal legs with the truck frame, and an elastic center bearing sus-

tained on said support comprising telescoping members and springs interposed between the same.

8. In a railway car truck, the combination 60 with a truck frame, of a center bearing support rigidly connected with the truck frame, an elastic center bearing comprising telescoping members and springs interposed between the same, and hangers for sustaining said center bearing on said support. 75

9. In a railway car, the combination with 70 a body bolster, its center plate, the truck frame and truck center plate, of telescoping members, hangers sustaining one of said telescoping members on the truck frame, the 80 other carrying said truck center plate, and springs interposed between said telescoping members.

10. In a railway car, the combination with 85 a body bolster, its center plate, the truck frame and truck center plate, of telescoping members, hangers sustaining one of said telescoping members on the truck frame, the other carrying said truck center plate, springs interposed between said telescoping 90 members, and a king pin extending through the center plates and telescoping members.

11. In a railway car, the combination with 95 a truck frame, a body bolster and a center bearing for the same, of an elastic oscillating center bearing support provided with legs extending diagonally with respect to the truck frame and rigid therewith.

12. In a railway car, the combination with 100 a truck frame and a body bolster, of a center bearing for the body bolster comprising telescoping members and springs interposed between the same, and a center bearing support provided with legs extending diagonally with respect to the truck frame and rigid 105 therewith.

13. In a railway car, the combination with 110 a truck frame and body bolster, of a center bearing for the body bolster comprising telescoping members and springs interposed between the same, a center bearing support formed with legs extending diagonally with respect to the truck frame and rigid therewith, and hangers sustaining said center bearing on said support. 115

14. In a railway car, the combination with 120 a truck frame comprising side members and transoms, a body bolster and a center bearing for the same, of a center bearing support provided with legs extending diagonally with respect to the truck frame, each secured to a side member and transom of the truck.

15. In a railway car truck, the combination 125 with a truck frame and a center bearing plate, of means sustained by said truck frame providing an elastic support for said center bearing plate, equalizer bars, and a plurality of coiled springs interposed between each equalizer bar and the corresponding side member of the truck frame 130

which come into play successively as the load increases.

16. In a railway car truck, the combination with a truck frame and a center bearing plate, of means sustained by said truck frame providing an elastic support for said center bearing plate, equalizer bars, a main spring, and on each side of the same auxiliary springs interposed between each equalizer bar and the corresponding side member of said truck frame.

17. In a railway car truck, the combination with a truck frame and a center bearing plate, of telescoping members one of which carries the center bearing plate and the other of which is sustained on said truck frame with capacity for oscillation transversely of the car, springs interposed between said telescoping members, equalizer bars, and springs interposed between the equalizer bars and the truck frame.

18. In a railway car truck, the combination with a truck frame and a center bearing plate, of telescoping members one of which carries the center bearing plate and the other of which is sustained on said truck frame, springs interposed between said telescoping members, equalizer bars, and a plurality of springs interposed between each equalizer bar and the corresponding side member of the truck frame which come into play successively as the load increases.

19. In a railway car truck, the combination with a truck frame and a center bearing plate, of telescoping members, one of which carries the center bearing plate, hangers providing a swinging support for the other telescoping member, springs interposed between said telescoping members, equalizer bars, and springs interposed between the equalizer bars and the truck frame.

20. In a railway car truck, the combination with a truck frame and a center bearing plate, of telescoping members, one of which carries the center bearing plate, hangers providing a swinging support for the other telescoping member, springs interposed between said telescoping members, equalizer bars, and a plurality of coiled springs interposed between each equalizer bar and the corresponding side member of the truck frame.

21. In a railway car truck, the combination with a truck frame, of a center bearing support rigidly connected with the truck frame, an elastic center bearing sustained on said support with capacity for oscillation transversely of the car, equalizer bars, and springs interposed between the equalizer bars and said truck frame.

22. In a railway car truck, the combination with a truck frame, of a center bearing support rigidly connected with the truck frame, an elastic center bearing sustained on said support, equalizer bars, and a plurality

of coiled springs interposed between each of said equalizer bars and the corresponding side member of said truck frame which come into play successively as the load increases.

23. In a railway car truck, the combination with a truck frame, of a center bearing support rigidly connected with the truck frame, an elastic center bearing sustained on said support with capacity for oscillation transversely of the car comprising telescoping members and springs interposed between the same, equalizer bars, and springs interposed between said equalizer bars and said truck frame.

24. In a railway car truck, the combination with a truck frame, of a center bearing support rigidly connected with the truck frame, an elastic center bearing sustained on said support comprising telescoping members and springs interposed between the same, equalizer bars, and a plurality of coiled springs interposed between each equalizer bar and the corresponding side member of said truck frame which come into play successively as the load increases.

25. In a railway car, the combination with a body bolster, its center plate, the truck frame and truck center plate, of telescoping members, hangers sustaining one of said telescoping members on the truck frame, the other carrying said truck center plate, springs interposed between said telescoping members, equalizer bars, and springs interposed between the equalizer bars and said truck frame.

26. In a railway car, the combination with a body bolster, its center plate, the truck frame and truck center plate, of telescoping members, hangers sustaining one of said telescoping members on the truck frame, the other carrying said truck center plate, springs interposed between said telescoping members, a king pin extending through the center plates and telescoping members, equalizer bars, and springs interposed between the equalizer bars and said truck frame.

27. In a railway car, the combination with a truck frame and a body bolster, of a center bearing for the body bolster comprising telescoping members and springs interposed between the same, a center bearing support provided with legs extending diagonally with respect to the truck frame and rigid therewith, equalizer bars, and springs interposed between the equalizer bars and said truck frame.

28. In a railway car, the combination with a truck frame and body bolster, of a center bearing for the body bolster comprising telescoping members and springs interposed between the same, a center bearing support formed with legs extending diagonally with respect to the truck frame and rigid therewith, hangers sustaining said center bearing

on said support, equalizer bars, and springs interposed between the equalizer bars and said truck frame.

29. In a railway car truck, the combination with a truck frame, of means for supporting the car body directly on said car truck frame, equalizer bars, and a plurality of springs interposed between each equalizer bar and the truck frame which bear directly against the latter and come into play successively as the load increases.

30. In a railway car truck, the combination with a truck frame, of means for elastically supporting the car body directly on said truck frame, equalizer bars, and a plurality of springs interposed between each equalizer bar and the truck frame which bear directly against the latter and come into play successively as the load increases.

20 31. In a railway car truck, the combination with a truck frame, of means providing an elastic swinging support for the car body directly upon said truck, equalizer bars, and a plurality of springs interposed between each equalizer bar and the truck frame which bear directly against the latter and come into play successively as the load increases.

32. In a railway car truck, the combination with a truck frame, of means for supporting the car body directly on said truck frame with capacity for oscillation transversely of the car comprising an elastic center bearing and elastic side bearings consisting in each case of telescoping members and spiral springs interposed between the same, equalizer bars, and springs interposed between the equalizer bars and the truck frame which bear directly against the latter.

40 33. In a railway car truck, the combination with a truck frame, of a center bearing and side bearings for supporting the car body directly upon said truck frame with capacity for oscillation transversely of the car, each of said bearings comprising telescoping members and springs interposed between said telescoping members, equalizer bars, and springs interposed between the equalizer bars and the truck frame which bear directly against the latter.

34. In a railway car truck, the combination with a truck frame, of a center bearing for supporting the car body directly upon said truck frame comprising telescoping members, springs interposed between the same and pivoted hangers, said bearings comprising members and springs interposed between the same, said car body having a sliding engagement with the upper telescoping member, equalizer bars, and springs interposed between the equalizer bars and the truck frame which bear directly against the latter.

65 35. In a railway car, the combination with a truck frame, of a telescoping member fixed

to said truck frame, a floating telescoping member, springs interposed between said members, and a bearing member on the car body having a slidable engagement with said floating telescoping member.

36. A center bearing for railway trucks comprising a lower telescoping member, an upper telescoping member provided with a center bearing plate, springs interposed between said telescoping members, and means for movably sustaining said lower telescoping member on the car truck.

37. In a railway car, the combination with a truck, a body bolster center plate and a truck center plate, of a pair of telescoping members, one of which carries said truck center plate and the other one of which is movably sustained on the truck, and springs interposed between said telescoping members.

20 38. In a truck, the combination with a truck frame, of equalizer bars, and a plurality of springs interposed between each equalizer bar and the truck frame which come into play successively as the load increases.

39. In a truck, the combination with a truck frame, of equalizer bars, and a plurality of springs interposed between each equalizer bar and the truck frame which bear directly against the latter and come into play successively as the load increases.

40. In a truck, the combination with a truck frame, of equalizer bars, and a plurality of coiled springs of different lengths interposed between each equalizer bar and the truck frame.

41. In a truck, the combination with a truck frame, of equalizer bars, a heavy coiled spring interposed between each equalizer bar and the truck frame, and a lighter, longer spring interposed between each equalizer bar and said truck frame.

42. In a truck, the combination with a truck frame, of equalizer bars, a heavy coiled spring interposed between each equalizer bar and the truck frame, and a lighter, longer spring interposed between each equalizer bar and said truck frame, arranged inwardly of the first named spring.

43. In a truck, the combination with a truck frame, of an elastic center bearing interposed between the body of the car and the truck frame, a plurality of equalizer bars, and a plurality of coiled springs of different lengths and degrees of resiliency interposed between each equalizer bar and the truck frame.

44. In a truck, the combination with a truck frame, of an elastic center bearing interposed between the body of the car and the truck frame, a plurality of equalizer bars, a heavy master spring interposed between each equalizer bar and the truck frame, and a longer, lighter spring inter-

posed between each equalizer bar and the truck frame.

45. In a railway car truck, the combination with a truck frame, of a center bearing supporting member provided with diagonal legs rigid with said truck frame and formed with a central opening, of a pair of telescoping members in said opening, spiral

springs interposed between said members, hangers for suspending the lower telescoping member, and a center bearing plate on the upper telescoping member.

It is hereby certified that in Letters Patent No. 1,128,771, granted February 16, 1915, upon the application of George H. Gilman, of St. Paul, Minnesota, for an improvement in "Railway-Car Trucks," errors appear in the printed specification requiring correction as follows: Page 3, line 49, for the word "sweeping" read *swing-ing*; same page, lines 54, 59, and 64, after the word "legs" insert the word *rigid*; same page, line 94, strike out the article "a" and insert the words *an elastic oscillat-ing*; and lines 95-96, strike out the words "an elastic oscillating;" and that the said Letters Patent should be read with these corrections therein that the same may conform to the record of the case in the Patent Office.

Signed and sealed this 16th day of March, A. D., 1915.

[SEAL.]

J. T. NEWTON,

Acting Commissioner of Patents.
